(57) **CLAIM**

The ornamental design for a durag, as shown and described.

DESCRIPTION

FIG. 1 is a front perspective view of a durag, showing my new design;

FIG. 2 is a front elevation view thereof, with the rear elevation view being a mirror image thereof;

FIG. 3 is a right side elevation view thereof;

FIG. 4 is a left side elevation view thereof;

FIG. 5 is a top plan view thereof;

FIG. 6 is a bottom plan view thereof; and,

FIG. 7 is a perspective view thereof, shown in use.

The broken line outline of the partial human figure in FIG. 7 assists in illustrating how the durag may appear when in a position of use, but forms no part of the claimed design.
